(21) Appl. No.: **29/256,570**

(57) **CLAIM**

(22) Filed: **Mar. 22, 2006**

I claim the single bowl sink, as shown and described.

(51) **LOC (8) Cl.** **23-02**

DESCRIPTION

(52) **U.S. Cl.** **D23/284**

FIG. 1 is a perspective view of a single bowl sink in accordance with the invention.

(58) **Field of Classification Search** D23/270-273,

FIG. 2 is a top elevation view of the single bowl sink shown in FIG. 1; and,

D23/284-287, 289, 291-293.1, 303, 308;
4/619, 630-631, 637, 661; D21/524

FIG. 3 is a cross-sectional view of the single bowl sink shown in FIGS. 1 and 2 and is taken about the line 3—3 shown in FIG. 2.

See application file for complete search history.

Broken lines shown in the drawings are environment and do not form part of the claimed design.
